UNITED STATES PATENT OFFICE.

WARREN H. TAYLOR, OF STAMFORD, CONNECTICUT, ASSIGNOR TO THE
YALE LOCK MANUFACTURING COMPANY, OF SAME PLACE.

APPARATUS FOR SLOTTING METAL.

SPECIFICATION forming part of Letters Patent No. 234,089, dated November 2, 1880.

Application filed April 11, 1878.

To all whom it may concern:

Be it known that I, WARREN H. TAYLOR, of Stamford, in the county of Fairfield and State of Connecticut, have invented an Improved Apparatus for Slotting Metal, of which the following is a specification.

The principle of my invention is simply that of cutting or sawing into work in devious lines to form irregular or curved kerfs that shall be exactly alike.

The particular purpose I have in view is to form sinuous key-slots in the hubs or cylinders of locks, which are adapted for the use of sheet-metal keys with side bits or serrations, like the ordinary "security" Yale lock-key. There are many practical considerations in favor of having the key-blade of such a key grooved or corrugated longitudinally, and there is little difficulty in properly corrugating such a key-blade in the process of manufacture by the use of suitable dies; but the formation of a corresponding keyway in the lock hub or cylinder has heretofore been attended with considerable difficulty; and it is the object of my invention to render it easy and economical to form such keyways that shall be uniform for particular patterns of hubs or cylinders and that shall neatly fit the respective standard keys.

In the accompanying drawings, Figure 1 is a plan view of my apparatus, showing the use of a gig-saw, and Fig. 2 is a longitudinal section of the same. Fig. 3 is a longitudinal section, showing the use of a band-saw; and Figs. 4 and 5 are detached sections, exhibiting details.

A indicates a table, bench, or bed-plate, through which the saw B works in an elongated transverse slot, b, to accommodate its vibrations. On this table is secured the reciprocating carriage C in suitable guideways D D. At the forward end of this carriage, immediately under the position of the work to be slotted, is a slot, c, forming an open way for the saw as the carriage is advanced to carry the work against it.

I employ a gig or band saw of the ordinary

kind for fine work, and it may be operated in any one of the usual ways.

On the under side of the carriage I secure a plate, F, containing a double-curved slot, f. I attach rigidly to the rotary saw-frame standard an arm or lever, G, which carries on its outer end a stud, H, provided with a friction-roller, h, that enters the slot f of the plate F. This arm contains an elongated transverse slot for the accommodation of the vibrations of the saw, like that in the bed-plate; but as the arm and saw vibrate together this slot need only be large enough to clear the saw. Now, the shape of slot f is such that as the carriage advances with the work to the saw the friction-roller on the stud impinges against the sides of the slot and gives to the arm G, and consequently to the rotary standard and saw, a vibratory motion, so that the direction of the saw in the work is constantly changing, and a sinuous kerf or slot is formed. This cut of the saw is determined as to its peculiar sinuosity and depth by the form of the cam-slot in the plate F, and all that will be necessary to get varying forms and depths of kerfs will be to take off one slotted plate and put on another with a different slot in its place.

The carriage may be reciprocated either by hand or power-driven mechanism, substantially such, for instance, as is used in small metal-planers.

Any suitable work-holder to secure the work to the carriage may be employed, and although I intend my apparatus particularly for cutting slots in key-hubs, it may be used for sinuously slotting other work.

When I use a band-saw I attach two arms, S S', rigidly to a rotary standard, T, behind the saw-blade, and provide them with hardened-steel guides or bushings t, that engage with the sides of the saw above and below the work without coming in contact with its teeth or back. The lower arm carries the stud and friction-roller, and is provided with an aperture, u, in front of the saw to prevent its teeth from striking the arm. The lateral vibrations of these arms in the manner already described

with respect to a gig-saw will cause the guides *t*, as the work-carrier advances, to bend or bear the band-saw slightly from side to side, so that it will form the desired irregular angular or curved kerf of uniform contour and depth in different key-hubs.

What I claim, and desire to secure by Letters Patent, is—

The combination of the vibrating saw, its

rotary standard, the arm carrying a stud secured to said standard, and the reciprocating slotted guide-plate, substantially as described.

In testimony whereof I have hereunto subscribed my name.

WARREN H. TAYLOR.
